(57) **CLAIM**

The ornamental design for a tiller head for electric pallet jack, as shown and described.

DESCRIPTION

FIG. 1 is a front view illustrating a tiller head for electric pallet jack, in accordance with the present invention;

FIG. 2 is a rear view thereof;

FIG. 3 is a first side view thereof;

FIG. 4 is an opposite side view thereof;

FIG. 5 is a front perspective view thereof;

FIG. 6 is an additional front perspective view thereof;

FIG. 7 is a rear perspective view thereof;

FIG. 8 is a top view thereof; and,

FIG. 9 is a bottom view thereof.

The broken lines in the drawings depict portions of the tiller head for electric pallet jack that form no part of the claimed design.
